(57) CLAIM

I claim the ornamental design for a display screen with icon, as shown and described.

DESCRIPTION

FIG. 1 is a front view of a display screen with icon; and, FIG. 2 is a front view of a second embodiment thereof.

The broken lines showing the display screen and other elements displayed on the screen are for the purpose of illustrating environmental structure and form no part of the claimed design.

1 Claim, 2 Drawing Sheets

FIG. 1

FIG. 2
